(57) **CLAIM**

The ornamental design for a faucet body, as shown and described.

DESCRIPTION

FIG. 1 is a perspective view taken from the top front and left side of a faucet body showing our new design for a faucet body;

FIG. 2 is a front elevational view thereof;

FIG. 3 is a top plan view thereof;

FIG. 4 is a left side elevational view thereof, the right side being a mirror image of the left side;

FIG. 5 is a rear elevational view thereof; and,

FIG. 6 is a bottom plan view thereof.

The broken line showing of the handles in FIGS. 1 and 2 and the apertures in FIG. 6 is for illustrative purposes only and forms no part of the claimed design.
